CLAIM

An ornamental design for a throwing game board, as shown and described.

DESCRIPTION

FIG. 1 is a front, right side isometric view of a throwing game board showing my new design;

FIG. 2 is a front elevational view thereof;

FIG. 3 is a rear elevational view thereof;

FIG. 4 a top elevational view thereof;

FIG. 5 is a bottom elevational view thereof;

FIG. 6 is a right side elevational view thereof; and,

FIG. 7 is a left side elevational view thereof.
